UNITED STATES PATENT OFFICE.

JAMES JESSEN, OF MINNEAPOLIS, MINNESOTA, ASSIGNOR TO HENRY O'B. HARDING,
OF MINNEAPOLIS, MINNESOTA.

BAG CLOSING AND TYING MACHINE.

1,196,460.

Specification of Letters Patent. Patented Aug. 29, 1916.

Application filed February 25, 1916. Serial No. 80,389.

To all whom it may concern:

Be it known that I, JAMES JESSEN, a citizen of the United States, residing at Minneapolis, in the county of Hennepin and State 5 of Minnesota, have invented certain new and useful Improvements in Bag Closing and Tying Machines, of which the following is a specification.

My invention relates to bag closing and 10 tying machines and has for its object to provide improved means for compacting and holding compacted the neck of a sack in such position that a portion of said neck is exposed above the compacting means and 15 adapted to receive loops of cord laid about the same by mechanism of the type disclosed in my co-pending application, Serial Number 21,020, filed April 13, 1915.

It is the object of my present invention to 20 provide improved means for fitting the neck of the sack into the tying head and compacting the same for fitting the body of the sack to the tying point and for discharging the sack after the same is tied together; with 25 safety means for preventing accidental operation of the device when certain parts are locked into position.

The full objects and advantages of my invention will appear in connection with the 30 detailed description thereof and are particularly pointed out in the claims.

In the drawings, illustrating the application of my invention in one form, Figure 1 is an elevational part sectional view of a 35 machine embodying my improvements. Fig. 2 is a part sectional plan showing some of the members in one position, and Fig. 3 is a similar plan showing the members in changed position, owing to the fit of the 40 sack. Fig. 4 is a vertical section taken on line 4-4 of Fig. 5. Fig. 5 is a top plan view showing generally the manner of tripping the mechanism for operating the bag-compacting means. Fig. 6 is an enlarged 45 view of some of the parts shown in Fig. 5. Fig. 7 is an elevational view of the parts for actuating the closure plate and tripper fingers. Fig. 8 is a sectional view through the tying plate and sack-mouth feeding 50 means taken on line 8-8 of Fig. 2 and drawn to a larger scale.

As illustrated, the machine is supported upon a standard 10 on which is a carriage 11 vertically adjustable by means of a worm

screw 12 and hand crank 13, said carriage comprising a platform 14 over which runs an endless belt 15 driven through a worm 16 slidable on a driving shaft 17. A looping finger 18 is operated by gearing 19 and lays the cord 20, which has its end secured by a 60 holder 21, in loops about the sack mouth, said cord extending through the looper 18 and tension devices 21' to a source of supply not shown. Power is obtained from a constantly-driven pulley 22, which through 65 shaft 23 and bevel gearing 24 continuously drives a pair of fluted rollers 25, 26 located above the tying plate 27 of the machine. The various sack-comprising and tying movements are intermittently effected from 70 the shaft 23 through a system of gearing 28 rendered operative by clutch means 29 which are actuated through a trip 30 mounted upon a sleeve 31 slidable upon shaft 23, the operation of said trip being effected by means 75 hereinafter described. The above parts are all substantially the same as those shown and described in the above enumerated application.

Generally speaking, the clutching mechanism referred to generally by the numeral 80 29 comprises an internal ratchet 32 which is engageable by a pivoted dog 33 on an arm 34. The arm 34 has driving connections with a cam drum 79 fast on the shaft 35 and 85 is normally held in inoperative position by a finger 36 on the trip 30 above referred to. The sleeve 31 has connected thereto a rod 37 which extends horizontally along the top of the machine and which is surrounded by a 90 spring 38 extended between a collar 39 thereon and a stand 40 in which the rod 37 has a bearing, the spring 38 acting to slide the sleeve 31 so as to hold the finger 36 in position to engage an arm or finger 41 on pawl 95 33 to hold the pawl inoperative. When rod 37 and sleeve 31 are slid so as to withdraw the finger 36 from the pawl arm 41 the pawl is thrown into engagement with a tooth of the internal ratchet 32 and the mechanism 100 controlled from cam 79 is operated. If, then, finger 36 is immediately restored to initial position the pawl 33 will be disengaged when the cam 79 has made one complete revolution.

Upon the constantly-driven shaft 42, which carries the crimping roller 26, is fast a gear 43 and a ratchet 44. A plate or disk

45 rests loosely upon the gear and ratchet and has thereon an arm 46 to which is pivoted a dog 47 adapted to engage the ratchet 44 and connect the plate to rotate with said 5 ratchet. Said dog 47 has fast thereon a finger 48 which is positioned so as to be engaged by a finger 49 on an arm 50 fast on a vertical rockshaft 51 journaled in a stand 52 connected with the main frame of the 10 machine. Connected to rotate with plate 45 by means of pin 53 extending through any one of a plurality of spaced apertures 54 in the disk 45 is a dog 55 adapted to engage a shoulder 56 on rod 37. It will be apparent 15 that when shaft 51 is oscillated the dog 47 will be released and will form a driving connection between constantly-driven gear 43 and plate 45 and dog 55 carried thereby. Dog 55 will then engage shoulder 56 and 20 slide the rod 37 and sleeve 31 against pressure of spring 38, withdrawing finger 36 so as to release dog 33 and clutch shaft 35 to constantly-driven gear 28.

The tying plate 27 is formed with an inner edge 57 curved as indicated at 58 and having a terminating recess at 59. Extending across the inner edge 57, as best 25 shown in Figs. 2, 6 and 7, so the end thereof comes below plate 27 and at the rear of 30 crimping rollers 25 and 26 is a finger 60, formed integral with an arm 61, which in turn is fast on shaft 51. When a sack is fed between the crimping rollers 25 and 26, as will later be pointed out, it engages finger 60, oscillates shaft 51 and withdraws toe 49, thus setting in action the train of 35 operations above described.

Spaced from the edge 57 of plate 27 so as to leave a passageway 62 between the edge 40 63 thereof and the edge 57, is a slide 64 which has a bead 65 that slides in a groove 66 on a base frame member 67 guiding said slide so that the same is adapted to move in a straight line. Within a transverse slot 68 45 in slide 64 is a roller 69 on an arm 70 which is fast on a vertical shaft 71 journaled in stand 52 and base member 67. A strong torsion spring 72 surrounding said shaft 71 has one end fast in stand 52 and the other 50 secured to a collar 73 which is pinned to shaft 71 and tends to rock the shaft 71 so as to carry arm 70 and slide 64 from the position shown in Fig. 6 to that shown in Fig. 3, thereby closing the passageway 62 55 from adjacent the crimping rollers 25 and 26 to the tying point 59. An arm 74 fast on shaft 71 has pivotally connected therewith a link 75 provided at its upper end with a cam roller 76, part of which runs in 60 a vertical guide slot 77 and the rest of which runs in a cam groove 78 on the cam drum 79 fast on shaft 35. The groove 78 extends around drum 79 along a single vertical plane or circumference of the drum, 65 excepting at one point where it is offset as

indicated at 80, having oblique walls as shown at 81 and a substantially right-angled drop as shown at 82 where it is positioned below roller 76 when the parts are at rest, as indicated in Figs. 5 and 6. A second arm 83 is formed integral with arm 74 and has a shoulder 84 thereon adapted to be engaged by a dog 85 fast on shaft 51 which holds the parts in normal inoperative position, as shown in Figs. 5 and 6, until shaft 51 is actuated through engagement of 70 sack with finger 60, as hereinbefore described. This will have the effect of withdrawing dog 85 from shoulder 84, which will permit spring 72 to act, with the result 80 that shaft 71 and arm 70 thereon will be rocked, carrying slide 64 from the position indicated in Fig. 2 to that shown in Fig. 3. At the same time link 75 and cam roller 76 will be drawn down so as to come to the inner limit of cam groove 78. The parts will 85 then be set in operation as heretofore described and cam drum 79 will be rotated with shaft 35. Before the termination of 90 said rotation the cam surfaces 81 in engagement with roller 76 will restore the parts to original position against the force of spring 72, and dog 85 will drop into position to engage shoulder 84 before cam roller 76 leaves the offset cam portion 80, a 95 spring 86 on shaft 51 tending at all times to hold the dog 85 in contact with the end of arm 83 as soon as the feed of the sack through passageway 62 releases finger 60.

In order to prevent accident through inadvertent shifting of rod 37 manually, which rod is in an exposed position, an arm 87 fast on shaft 51 has a toe 88 in engagement with the end of rod 37, by which means 100 manual movement of rod 37 will oscillate 105 shaft 51 and withdraw dog 85, thus insuring simply a normal operation of the machine.

After the sack mouth has been carried into the closed passageway 62 by means of the feed rollers 25 and 26 it is necessary that the sack mouth shall be compacted at the 110 tying point 59, and this is effected by a pusher bar 89. This bar is pivotally connected at one end to an operating arm 90 115 and has adjacent the other end a cam roller 91 operative in a cam slot 92 formed in plate 27, said cam slot, as best shown in Fig. 6, is provided with a branch 93 curved away from the passageway 62. Adjacent the 120 roller 91 the pusher 89 is provided with an engaging head 94, which it will be seen is held at one side of passageway 62 when the 125 pusher bar 89 is fully retracted and the roller 91 carried to one side into branch 93 of cam slot 92. Arm 90 is journaled on a stub shaft 96 and has an extension 97 at one side of an arm 98, also journaled on shaft 96, and has a pin 99 held in a socket at the end of arm 97 and provided with a collar 130

100 between which and a plate 101 on arm 98 is a powerful compression spring 102. The arm 101 is provided with a cam roller 103 which enters a cam groove 104 in cam 5 drum 79. Groove 104 is of such shape that when the cam drum is set in motion by the means hereinbefore described, the arm 98 will, at the proper time in the sequence of operations and after the expanded sack mouth 105 (shown in Fig. 2) has been fed past rollers 25 and 26, be rocked from the position shown in full lines to that shown in dotted lines in Fig. 3. This moves pusher bar 89 forward and engagement of roller 91 10 in slot 92, 93 first causes head 94 to be moved across passageway 62 and then causes said head to follow the passageway to the position of the same shown in dotted lines in Fig. 3, where the sack mouth is compacted 15 in slot 92, 93 first causes head 94 to be moved across passageway 62 and then causes said head to follow the passageway to the position of the same shown in dotted lines in Fig. 3, where the sack mouth is compacted 20 at the end of the passageway 62 as indicated at 59. A groove 106 in the side of pusher 89 receives a tongue 107 formed on plate 27, beneath which and along a slot 108 formed in the side wall of plate 27, as best shown 25 in Figs. 1 and 4, the body of the pusher is operated. By this means the pusher is held from movement up or down as it is moved to compacting position, and the sack material is prevented from entering between the 30 pusher and sides of passageway 62. The spring 102 permits sufficient yielding to allow for variations in the aggregate size of the compacted sack mouth and to prevent cutting the material of the sack or injuring 35 any of the parts. It will be observed that the pusher operates underneath the feeding rollers 25 and 26, which are spaced sufficiently above the plane of plate 27 to permit this, as clearly shown in Fig. 1. At the entrance of passageway 62, and also positioned 40 so as to leave a space between the lower ends thereof and the top plane of plate 27 are a pair of guide members 110 and 111, each of which curves outwardly as shown in Figs. 45 2 and 3, forming an effective means for readily guiding the edge of the sack mouth 105 into passageway 62.

As heretofore stated, the endless belt 15 is driven through a worm 16 splined on a shaft 50 17. As best shown in Fig. 8, this shaft is normally driven through a bevel gear 112 on the end of shaft 17 which meshes with a bevel gear 113 having its hub 133 loose on a shaft 114 journaled in the parallel arms of 55 a bracket 115. Shaft 114 has thereon a bevel gear 116 which meshes with a bevel gear 117 on constantly-driven shaft 23. A clutch 118 is splined on shaft 114 and is controlled by a clutch fork 119 pivoted at 60 120 to bracket 115 and having fast with the arm thereof an arm 121 which engages a cam 122 on cam drum 79. The cam 122 is for the major portion of its length relatively raised, having a depressed portion 123 with 65 a sloping wall 124 on one side and an abrupt wall 125 on the other. A roller 126 on the end of arm 121 is normally held in the depressed portion 123 by a spring 127 surrounding shaft 114 and engaging clutch 118. Driving connection is thus normally 70 established through hub or sleeve 133 and bevel gear 113 with shaft 17 and worm 16, so that endless belt 15 will normally be in operation. Immediately after cam 79 has been set in operation by the means heretofore described, the roller 126 will run up the sloping portion 124 at the side of depression 123, which will slide clutch 118 and terminate driving action of belt 15. This will take place just after the sack has been 80 moved to the position indicated by full lines in Fig. 1 and just before the completion of the compacting movement of pusher 89. The endless belt runs over platform 14 and a sack-receiving platform 128 overlies a 85 portion of the belt, as shown in Fig. 1, leaving only a part 129 of belt 15 exposed. The filled sacks are moved from the weighing machine upon the platform 128 and slid by the operator off from said platform upon 90 the receiving portion 129 of endless belt. The body of the sack is forwarded by said moving belt at the same time that the expanded sack mouth 105 is carried into passageway 62 and fed through the same first 95 by the feeding rollers 25, 26 and thereafter by pusher head 94. As heretofore pointed out, the movement of sack mouth 105 through passageway 62 causes it to engage finger 60, which operates simultaneously to 100 withdraw dog 85, releasing slide 63, and to withdraw toe 49, releasing dog 47 and setting in operation the dog 55 on plate 45. Dog 55 is spaced from shoulder 56 (by the adjustable connection through holes 54) so 105 that it will engage said shoulder and operate shifter rod 37 so as to clutch into operation shaft 35 just after the complete sack mouth 105 has been fed past the pusher head 94. The cam drum 79 will then be set in 110 motion, the first operations of which will be to actuate pusher 89 and terminate driving action of endless belt 15 with the sack in the position indicated in full lines in Fig. 1. At the expiration of a complete revolution 115 of cam drum 79 the slide 64 will be retracted through operation of cam wall 81 of cam groove 78 upon roller 76, pusher slide 89 will also be withdrawn, and immediately preceding which the roller 126 will drop 120 over the abrupt wall 125 into depression 123 and the drive of endless belt 15 will be resumed. The lower end of the sack will begin to be fed off over the roller 131 which carries the front end of endless belt 15 toward a slide 132 which has a wall 134 adjustably connected with a wall 135 of a trough having therein an endless carrier 136. At the time of or just before the belt resumes feeding action, the compacted sack 125 130

mouth will be released by withdrawal of slide 64 and pusher head 94, leaving the large opening 130 through which said sack mouth may readily pass, the sack falling by gravity as indicated in dotted lines in Fig. 1 over slide 132 and upon endless carrier 136.

I claim:

1. A machine for operating upon sacks comprising means for receiving the mouth of a sack including a fixed member and a movable member positioned in a common plane and spaced from one another so as to form a passageway, means for moving the movable member to prolong the parallel walled passageway, and means controlled by movement of the sack mouth for rendering said moving means operative. 75
2. A machine for operating upon sacks comprising sack-mouth feeding means, fixed and movable plates spaced from one another in a common plane to form a passageway through which the sack is fed, means controlled by movement of the sack through the passageway for moving the movable plate to extend said passageway, and means thereafter for restoring the movable plate to initial position. 80
3. A machine for operating upon sacks comprising a plate having a wall extending to a tying head, a movable plate having a wall parallel with and spaced from said first-named wall and normally extending some distance short of the tying head, means for feeding the sack mouth, and means set in operation after the beginning of feed of the sack for moving the movable plate to the tying head so as to complete the passageway thereto. 85
4. A machine for operating upon sacks comprising sack-mouth feeding means, a fixed plate, a movable plate shorter than the fixed plate and spaced therefrom to form a passageway along which the sack mouth is fed, means holding the movable plate in a rearward position, means tending to move the movable plate quickly into its forward position, and means for releasing said holding means to permit such quick movement. 90
5. A machine for operating upon sacks comprising sack-mouth feeding means, a fixed plate, a movable plate shorter than the fixed plate and spaced therefrom to form a passageway along which the sack mouth is fed, means holding the movable plate in a rearward position, means tending to move the movable plate quickly into its forward position, and means extending across the passageway and actuated by movement of the sack therethrough for releasing the holding means to permit such quick movement. 95
6. A machine for operating upon sacks comprising sack-mouth feeding means, a fixed plate, a movable plate shorter than the fixed plate and spaced therefrom to form a passageway along which the sack mouth is fed, means holding the movable plate in a rearward position, means tending to move the movable plate quickly into its forward position, and means extending across the passageway and actuated by movement of the sack therethrough for releasing the holding means to permit such quick movement. 100
7. A machine for operating upon sacks comprising sack-mouth feeding means, a fixed plate, a movable plate shorter than the fixed plate and spaced therefrom to form a passageway along which the sack mouth is fed, means holding the movable plate in a rearward position, means including a spring held set by the holding means tending to move the movable member quickly into its forward position, and means for releasing the spring. 105
8. A machine for operating upon sacks comprising means for receiving the mouth of a sack including a fixed member and a movable member positioned in a common plane and spaced from one another so as to form a passageway, means tending to move the movable member to prolong the parallel walled passageway, constantly-operating sack-mouth feeding means, intermittently-operative means for forwarding and compacting the sack mouth at the end of said passageway, and means controlled by movement of the sack mouth by said feeding means for rendering operative the means for moving the movable member. 110
9. A machine for operating upon sacks comprising continuously-operative sack-mouth feeding means, fixed and movable plates spaced from one another in a common plane to form a passageway through which the sack is fed, means controlled by movement of the sack through the passageway by said feeding means for moving the movable plate to extend the passageway, and an intermittently-operative pusher for forwarding said sack mouth through said extended passageway and compacting the same at the end thereof. 115
10. A machine for operating upon sacks comprising continuously-operative sack-mouth feeding means, fixed and movable plates spaced from one another in a common plane to form a passageway through which the sack is fed, means controlled by movement of the sack through the passageway by said feeding means for moving the movable plate to extend the passageway, an intermittently-operative pusher for forwarding said sack mouth through said extended passageway and compacting the same at the end thereof, and means thereafter for withdrawing the pusher and re- 120
11. A machine for operating upon sacks comprising continuously-operative sack-mouth feeding means, fixed and movable plates spaced from one another in a common plane to form a passageway through which the sack is fed, means controlled by movement of the sack through the passageway by said feeding means for moving the movable plate to extend the passageway, an intermittently-operative pusher for forwarding said sack mouth through said extended passageway and compacting the same at the end thereof, and means thereafter for withdrawing the pusher and re- 125
12. A machine for operating upon sacks comprising continuously-operative sack-mouth feeding means, fixed and movable plates spaced from one another in a common plane to form a passageway through which the sack is fed, means controlled by movement of the sack through the passageway by said feeding means for moving the movable plate to extend the passageway, an intermittently-operative pusher for forwarding said sack mouth through said extended passageway and compacting the same at the end thereof, and means thereafter for withdrawing the pusher and re- 130

storing the movable plate to initial position to release the sack mouth.

11. A machine for operating upon sacks comprising continuously-operative sack-mouth feeding means, fixed and movable plates spaced from one another in a common plane to form a parallel-walled passageway through which the sack is fed, means controlled by movement of the sack through the passageway for moving the movable plate to extend said passageway, a pusher for forwarding the sack mouth through said extended passageway and compacting the same at the end thereof, and means set in operation by actuation of said sack-controlled means for operating the pusher.

12. A machine for operating upon sacks comprising continuously-operative sack-mouth feeding means, fixed and movable plates spaced from one another in a common plane to form a parallel-walled passageway through which the sack is fed, means controlled by movement of the sack through the passageway for moving the movable plate to extend said passageway, a pusher for forwarding the sack mouth through said extended passageway and compacting the same at the end thereof, means set in operation by actuation of said sack-controlled means for operating the pusher, and means thereafter for withdrawing the pusher and restoring the movable plate to initial position to release the sack mouth.

13. A machine for operating upon sacks comprising spaced members forming a passageway between the same for receiving the extended mouth of the sack, and a pair of members upwardly-extended and curved away from the entrance to said passageway for guiding the sack mouth thereto.

14. A machine for operating upon sacks comprising spaced members forming a passageway between the same for receiving the extended mouth of the sack, a pair of members upwardly-extended and curved away from the entrance to said passageway for guiding the sack mouth thereto, continuously-operative means for feeding the sack mouth along said passageway, and intermittently-operative means for forwarding the sack mouth through said passageway and compacting the same at the end thereof.

15. A machine for operating upon sacks comprising spaced members forming a passageway between the same for receiving the extended mouth of the sack, a pair of members upwardly-extended and curved away from the entrance to said passageway for guiding the sack mouth thereto, a pusher having an engaging portion normally held at one side of said passageway, and means for intermittently operating the pusher to bring said engaging portion into the passageway and below said last-named members and thereafter to move the same along

the passageway for forwarding the sack mouth through said passageway and compacting the same at the end thereof.

16. A machine for operating upon sacks comprising spaced members forming a passageway between the same for receiving the extended mouth of the sack, means for carrying the mouth of the sack into said passageway, a pusher having an engaging portion thereof normally held at one side of the passageway, and means for operating the pusher to cause said engaging portion to enter the passageway and thereafter to move the same along the passageway for forwarding the sack mouth through said passageway and compacting the same at the end thereof.

17. A machine for operating upon sacks comprising spaced members forming an extended passageway between the same for receiving the extended mouth of the sack, one of said members having a cam slot therein with a branch curving away from the passageway, means for carrying the mouth of the sack into the passageway, a pusher bar having a cam roller operative in said slot whereby in the retracted position of the bar the engaging end thereof will be held at one side of the passageway, and means for periodically actuating the bar, said roller and slot operating to carry the engaging portion of the bar into the passageway and thereafter guide the same along said passageway for forwarding the sack mouth and compacting the same at the end of the passageway.

18. A machine for operating upon sacks comprising spaced members forming an extended passageway between the same for receiving the extended mouth of the sack, one of said members having a cam slot therein with a branch curving away from the passageway, means for carrying the mouth of the sack into the passageway, a pusher bar having a cam roller operative in said slot whereby in the retracted position of the bar the engaging end thereof will be held at one side of the passageway, means for periodically actuating the bar, said roller and slot operating to carry the engaging portion of the bar into the passageway and thereafter guide the same along said passageway for forwarding the sack mouth and compacting the same at the end of the passageway, said pusher bar being formed with a groove in the side thereof, and a guide rib for entering said groove to steady the pusher member as the same is operated.

19. A machine for operating upon sacks comprising spaced members forming a passageway between the same for receiving the extended mouth of the sack, continuously-operative means above the plane of said members for feeding the sack along said passageway, a pusher having an engaging

- portion normally held at one side of said passageway and in a plane below said feeding means, and means for intermittently operating the pusher to bring said engaging portion into the passageway and thereafter to move the same along the passageway and below said feeding means for forwarding the sack mouth through said passageway and compacting the same at the end thereof. 5
- 10 20. A machine for operating upon sacks comprising a tying head and means for feeding the mouth of the sack thereto and compacting the same, sack-forwarding means embodying a pair of platforms, and an endless belt running between said platforms and having a portion exposed above the lower and beyond the end of the upper of said platforms and extending to a point beneath the tying head. 15
- 15 21. A machine for operating upon sacks comprising a tying head and means for feeding the mouth of the sack thereto and compacting the same, sack-forwarding means embodying a pair of platforms, an endless belt running between said platforms and having a portion exposed above the lower and beyond the end of the upper of said platforms, a front roller for driving said endless belt having its axis immediately beneath the tying head, and a chute extending tangential to said roller. 20
- 20 22. A machine for operating upon sacks comprising a tying head and means for feeding the mouth of the sack thereto and compacting the same, sack-forwarding means embodying a pair of platforms, an endless belt running between said platforms and having a portion exposed above the lower and beyond the end of the upper of said platforms and extending to a point beneath the tying head, normally-operative means for driving said belt, and means controlled by feed of the sack mouth to the tying head for intermittently terminating operation of said belt. 25
- 25 40 45 23. A machine for operating upon sacks comprising a tying head and means for feeding the mouth of the sack thereto and compacting the same, sack-forwarding means embodying a pair of platforms, an endless belt running between said platforms and having a portion exposed above the lower and beyond the end of the upper of said platforms and extending to a point beneath the tying head, normally-operative means for driving said belt, means controlled by feed of the sack mouth to the tying head for intermittently terminating operation of said belt. 30
- 30 45 50 55 24. A machine for operating upon sacks comprising a tying head and means for feeding the mouth of the sack thereto and compacting and holding the same, a platform for receiving and feeding the body of the sack including an endless belt, normally-operative means for driving said belt, means controlled by feed of the sack mouth to the tying head for intermittently terminating operation of said belt, and means thereafter operative to release the compacted mouth and render the belt driving means operative. 35
- 35 40 45 50 55 25. A machine for operating upon sacks comprising a tying head and means for feeding the mouth of the sack thereto and compacting and holding the same, a platform for receiving and feeding the body of the sack including an endless belt, normally-operative means for driving said belt, means controlled by feed of the sack mouth to the tying head for intermittently terminating operation of said belt, means thereafter operative to release the compacted mouth and render the belt driving means operative, and means for rendering operative said belt driving means after the release of the sack. 40
- 40 45 50 55 26. A machine for operating upon sacks comprising a tying head and means for feeding the mouth of the sack thereto and compacting and holding the same, sack-forwarding means embodying an endless belt, a front roller for driving said endless belt having its axis immediately beneath the tying head, a chute having the bottom wall thereof extending tangential to said roller, normally-operative means for driving said belt, means controlled by feed of the sack mouth to the tying head for intermittently rendering said driving means inoperative to stop the belt for a definitely-timed period and thereafter to restore operation of the driving means and start the belt, and means for releasing the compacted sack mouth before the belt is started. 45
- 45 50 55 27. In testimony whereof I affix my signature in presence of two witnesses. 50

JAMES JESSEN.
